United States Patent Office

Des. 198,800
Patented Aug. 4, 1964

198,800

CABINET

Norman N. Hekler, High Point, N.C., assignor to Worth Furniture, a division of Gravely Furniture Co., Inc., Martinsville, Va., a corporation of Virginia

Filed Mar. 26, 1963, Ser. No. 74,138

Term of patent 3½ years

(Cl. D33—19)

FIG. 1.

FIG. 2.

FIG. 1 is a top plan view of a cabinet showing my new design;

FIG. 2 is a side elevational view thereof.

The five undisclosed vertical faces of the cabinet are the same in configuration as the two outer faces shown in FIG. 2.

I claim:

The ornamental design for a cabinet, as shown and described.
